UNITED STATES PATENT OFFICE.

ISAAC SNOW, OF LAWRENCE, MASSACHUSETTS, ASSIGNOR TO DRAPER CORPORATION,
OF HOPEDALE, MASSACHUSETTS, A CORPORATION OF MAINE.

FEELER MECHANISM FOR LOOMS.

Application filed February 25, 1922. Serial No. 539,140.

To all whom it may concern:

Be it known that ISAAC SNOW, a citizen of the United States, and resident of Lawrence, in the county of Essex and State of Massachusetts, has invented an Improvement in Feeler Mechanisms for Looms, of which the following description, in connection with the accompanying drawings, is a specification, like characters on the drawings representing like parts.

This invention relates to feeler mechanisms for looms, wherein a change in the operation of the loom is effected when the filling in the running shuttle reaches substantial exhaustion, but prior to complete exhaustion.

A variety of feeler mechanisms have been suggested for this purpose, and in that type of feeler mechanism known as the "side swipe," wherein the feeler has a detecting movement in a direction longitudinally of the shuttle, the feeler is given a tendency on each detecting beat to partake of its detecting movement under the impulse of some yielding means or in some cases, by the forward pressure upon the feeler. This constantly-recurring tendency of the feeler to partake of its filling exhaustion detecting movement is normally resisted by engagement of the toothed or frictional end of the feeler with the filling so long as a working supply is present in the shuttle; but the filling itself is liable to be injured or displaced upon the filling carrier in the shuttle under the constantly-recurring tendency of the feeler to partake of its detecting function.

One of the purposes of the present invention is to provide a feeler mechanism wherein the feeler will have no tendency to partake of its detecting movement until the filling has reached or approached a degree of substantial exhaustion, whereupon on each following detecting beat, the means for giving the feeler its detecting movement acts functionally to impart its detecting tendency.

Attempts have heretofore been made to overcome these objections and obviate the injurious effect upon the filling by providing a lock or some means for preventing detecting movement of the feeler until the filling has approached a degree of substantial exhaustion, and thereupon to free the feeler for movement in response to the force tending to impart its detecting movement.

An important feature of the present invention, therefore, consists of a feeler which normally has no tendency to functionally detect substantial exhaustion of filling while still free to such movement, and means which comes into action to impart detecting movement to the feeler only when the filling approaches substantial exhaustion. In some aspects of the present invention the feeler may be of different types, but as shown and described in the present instance, the feeler is of the side swipe type, normally free to move longitudinally of the shuttle, but in which the moving force becomes active only when the filling approaches substantial exhaustion.

The invention and the various novel features and combination of parts will best be made clear from the following description and accompanying drawings of one good form of the invention.

In the drawings:—

Figure 1 is a perspective view of the detecting side of the loom, showing more particularly the feeler mechanism and its associated parts;

Fig. 2 is a plan view, showing the action of the feeler mechanism, when a working supply of filling is present in the shuttle on a detecting beat; and

Fig. 3 is a view similar to that of Fig. 2, showing the action of the feeler mechanism when the filling is substantially exhausted on a detecting beat.

The loom frame 1 of usual construction, is provided with the brackets 2 having bearings 3, one at each side of the loom, in which is supported the transverse or rock shaft 4. Rising from the transverse or rock shaft 4 is an arm 5, to the upper end of which is connected at 6 the actuator or arm 7, the rear end portion 8 of which is adapted to be engaged by an operating means 9 for moving the operator or arm 7 forwardly when, on a detecting beat, the filling is detected by the feeler as substantially exhausted.

The operating means 9 may be conveniently attached to or formed as part of the weft hammer or cam follower, and in the present instance of the invention, the end 8 of the actuator 7 is normally in inoperative position with respect to the operating means 9, and is moved into operative position when the feeler detects substantial exhaustion of filling.

In the present instance of the invention, the actuator 7 is shown as having a member 10 under which is positioned the arm 11 of a lever pivotally mounted at 12 on a support such as the arm 13 secured to a lug or projection 14 on the loom frame or shipper stand, the construction being such that the end 8 of the actuator 7 will normally stand below the engaging portion of the operating means 9 and may be raised into operative position when the end 11 of the lever is turned by the feeler as will more fully appear.

Adjustably mounted on an extension 15 from the shipper stand, is a bracket 16 having a supporting portion 17 for the feeler stand 18, which may be adjustably secured thereto as by the bolt 19 and slot 20.

The feeler stand 18 is provided with a rocking bearing 21 which may be conveniently formed by a block mounted on an axis 22 supported between a bracket 23 and the feeler stand. The parts so far described may be of any usual construction.

The rear portion of the feeler stand 18 is provided with a bearing 24 in which is mounted the slide 25, capable of lateral movement in the bearing 24, and connected to the lug 26 of the slide 25 is a transmitter 27 which is connected to the lever 11 at 28, the construction being such that the weight of the actuator 7 on the lever 11 normally holds the slide 25 to the right as indicated in Fig. 1.

The feeler 29 passes through the slide 25 and also through the elongated slot 30 formed in the bearing 24, the construction being such that the feeler 29 and the slide 25 may move laterally or in a direction longitudinally of the shuttle in the bearing 24.

Extending frontwardly from the feeler 29 is the stem 31 which passes through an opening 32 in the rocking bearing 21; and surrounding the stem 31 is a spring 33 which normally holds the feeler in its rearward feeling position. In the present instance the spring 33 at its front end bears against the rocking bearing 21, and at its rear end bears against a shoulder or abutment 34 formed on the feeler, a stop 35 acting to define the rearward position of the feeler. The described construction is a convenient and good practical form of means for supporting the feeler for movement frontward and rearward of the loom, and also in a direction longitudinally of the shuttle, but the advantages of the present invention may be appropriately secured by other forms of construction permitting the described feeler movements.

The lay 36 is or may be of usual construction, and has the shuttle-box 37 which is provided with an opening 38 in its front wall

for the entrance of the feeler on each detecting beat to feel for the filling in the shuttle then positioned in the detecting box. The shuttle 39, in which is mounted the filling carrier 40, also has its front wall provided with a slot 41, the construction being such that on a detecting beat the feeler 29 may pass through the front wall of the shuttle-box and shuttle and feel for the filling.

A feeler displacer is movable with the lay and is preferably mounted thereon to act upon the feeler and impart a tendency of the feeler to partake of its detecting movement longitudinally of the shuttle only when the filling has been depleted to a predetermined extent. The feeler displacer in the present instance comprises an arm 42 which is mounted for reciprocating movements in a direction longitudinally of the shuttle in brackets 43 carried by the lay, and as a preferred form of the feeler displacer, a spring 44 is interposed between the brackets 43, one end of the spring—that to the right—bearing upon the adjacent bracket 43, and the other end of the spring bearing upon a shoulder 45 formed as part of or secured to the displacer 42, the construction being such that while the displacer is carried on the lay by the brackets 42 or equivalent means, the spring 44 normally holds the displacer 42 in its projected position as indicated in Figs. 1 and 2, with permissive movement, however, of the displacer 42 in opposition to the spring 44.

The active end portion of the displacer 42 may, in some instances, be provided with a roller 46 carried between the bifurcated end portions 47 of the displacer, and preferably the active end portion of the displacer or roller 46 is normally positioned opposite or adjacent the openings 38 and 41 in the front wall of the shuttle-box and shuttle.

As hereinbefore noted, the present invention contemplates that the feeler shall not injuriously affect the filling when a working supply is present in the shuttle, by the tendency of the feeler to partake of its detecting movement until the filling has reached a degree of substantial exhaustion. To this end the feeler 29 in the present instance is provided with a projection or cam portion 48 between the rear end 49 of the feeler and the bearing 24, and so positioned with respect to the rear end of the feeler that when a working supply of filling is present in the shuttle on a detecting beat, and the feeler, therefore, enters the shuttle a less distance than it does when the filling is substantially exhausted, the feeler displacer will fail to engage with the projection or cam 48 as the displacer is moved frontwardly by the lay. Thus, when a working supply of filling is present in the shuttle on a detecting beat, the feeler has no tendency to partake of its

- detecting movement, but engages the filling and is moved frontwardly by the filling against the normal tendency of the spring 33 which, in view of the fact that the spring's sole purpose is to maintain the feeler in its rearward feeling position, may be relatively light and consequently not cause injury to the filling by the constantly-recurring engagements therewith.
- 10 When the filling reaches a degree of substantial exhaustion or approaches that condition, the feeler will enter further into the shuttle as the lay moves frontwardly on a detecting beat, or in other words, the feeler 15 will measure the diameter of the filling on the filling carrier, and when the filling is nearly exhausted, the feeler displacer will engage the projecting or cam portion 48 of the feeler and impart to the feeler a tendency 20 to partake its detecting movement, which in the present instance is longitudinally of the shuttle.

In case the rear end portion of the feeler has a smooth surface, as may be sometimes preferable owing to the character of the filling in use, the feeler displacer will effect movement of the feeler longitudinally of the shuttle when the feeler is permitted to enter the shuttle the predetermined distance, determined by the substantial exhaustion or decreased diameter of the filling; but in case the feeler is provided with filling-engaging teeth, which may sometimes be desirable, the feeler displacer will act progressively more 35 and more upon the feeler as the filling becomes progressively depleted and the teeth of the feeler will hold the feeler from partaking of its movement longitudinally of the shuttle until the shuttle displacer rides well 40 up on the cam 48 of the feeler, the spring 44, acting yieldingly upon the displacer to permit the feeler to move the displacer so long as sufficient filling remains in the shuttle to continue the weaving operation.

45 In the present instance of the invention, therefore, while the feeler is free to partake of its side swipe movement even when a working supply of filling is present in the shuttle, the force tending to impart such side swipe movement to the feeler remains quiescent or non-active, and comes into action only when the feeler enters the shuttle an unusual amount due to the substantial or approach to substantial exhaustion of the filling.

50 What is claimed is: —

1. In a feeler mechanism for looms, the combination of a feeler that enters the shuttle on each detecting beat of the lay to feel for the filling, a feeler displacer mounted on the lay to bear upon the side of the feeler and move it in a direction longitudinally of the shuttle due to the forward movement of the lay when the filling is substantially exhausted on a detecting beat, and means actu-

ated by movement of the feeler induced by the displacer for effecting replenishment of filling.

2. In a feeler mechanism for looms, the combination of a feeler having a filling exhaustion indicating movement in a direction longitudinally of the shuttle, a feeler displacer that is moved by the lay in a direction longitudinally of the feeler and relative thereto and is ineffective to impart filling exhaustion indicating movement to the feeler until the filling is substantially exhausted, and means for causing replenishment of filling by displacer-induced movement of the feeler on a detecting beat 75 of the lay.

3. In a feeler mechanism for looms, the combination of a feeler mounted to feel for the filling on each detecting beat of the lay and frontwardly displaced by the filling 80 until the filling is substantially exhausted and then displaced to a less extent, a feeler displacer connected to the lay and normally ineffectual to impart any tendency of the feeler to partake of its filling exhaustion 85 indicating movement until the filling approaches substantial exhaustion and to thereupon become effectual and cause detecting movement of the feeler when the filling is to be changed, and means actuated 90 by displacer-induced movement of the feeler to cause replenishment of filling.

4. In a feeler mechanism for looms, the combination of a feeler mounted to feel for the filling in the shuttle, a feeler displacer 100 moved relatively to and along the feeler by the lay on a detecting beat, and acting to impart to the feeler a tendency to partake of its detecting movement when the filling in the shuttle approaches substantial exhaustion 105 on a detecting beat, and means actuated by displacer-induced movement of the feeler for effecting replenishment of filling.

5. In a feeler mechanism for looms, the combination of a feeler that enters the shuttle on a detecting beat and feels for the filling, a feeler displacer mounted on the lay, said feeler and feeler displacer having portions which engage when the feeler enters the shuttle to a predetermined extent 110 on a detecting beat and by such engagement tend to effect movement of the feeler longitudinally of the shuttle, and means for replenishing the filling when the feeler is so 115 moved by the feeler displacer.

6. In a feeler mechanism for looms, the combination of the lay, a feeler mounted independent of the lay for movement toward and from the front of the loom and 120 also in a direction longitudinally of the shuttle, and a feeler displacer mounted on the lay for imparting to the feeler its filling exhaustion indicating movement longitudinally of the shuttle on a detecting beat 125 130

only when the feeler enters the shuttle to a predetermined extent and means for effecting replenishment of filling when the feeler is moved by the displacer.

5 7. In a feeler mechanism for looms, the combination of a feeler that feels for the filling in the shuttle on a detecting beat, a feeler displacer that is moved frontwardly relative to the feeler on a detecting beat, said feeler and feeler displacer having portions which contact with each other on a detecting beat only when the filling approaches substantial exhaustion and by such engagement tend to impart to the feeler its filling exhaustion indicating movement, and means for causing replenishment of filling when the feeler partakes of its indicating movement.

20 8. In a feeler mechanism for looms, the combination of a feeler that enters the shuttle on each detecting beat to measure the filling wound on the filling carrier, a feeler displacer mounted on the lay and movable frontwardly thereby alongside the feeler, for engaging a part carried by the feeler due to the relative movement of the feeler and feeler displacer and causing the feeler displacer to impart a tendency to the feeler to indicate substantial exhaustion of filling when the feeler measures an approach to substantial exhaustion.

9. In a feeler mechanism for looms, the combination of a feeler mounted on the loom in front of the lay and normally held in its rearward feeling position by a light 35 spring to cause non-injurious contact with the filling in the shuttle on detecting beats, a feeler displacer connected to and movable with the lay, and a projection on the feeler that engages the feeler displacer when the 40 filling has reached a condition of substantial exhaustion to cause filling exhaustion indicating movement of the feeler and effect replenishment of filling.

10. In a feeler mechanism for looms, the 45 combination of a side swipe feeler which calls for a change of filling by movement in a direction longitudinally of the shuttle and has teeth which engage the filling on a detecting beat and prevent movement of 50 the feeler longitudinally of the shuttle until the filling is substantially exhausted, a feeler displacer movable frontwardly on each detecting beat, said feeler and feeler displacer having portions that engage each 55 other only when the filling is nearly exhausted on a detecting beat and by such engagement tend to impart to the feeler its filling exhaustion indicating movement.

In testimony whereof, I have signed my 50 name to this specification.

ISAAC SNOW.
